UNITED STATES PATENT OFFICE.

EMIL BOMMER, OF BROOKLYN, NEW YORK, ASSIGNOR TO EMIL BOMMER PLAY-GROUNDS FOUNDATION, INC., OF BROOKLYN, NEW YORK, A CORPORATION OF NEW YORK.

GAME.

Application filed August 6, 1925. Serial No. 48,452.

To all whom it may concern:

Be it known that I, EMIL BOMMER, a citizen of the United States, and resident of Brooklyn, in the county of Kings and State 5 of New York, have invented certain new and useful Improvements in Games, of which the following is a specification.

This invention relates to games, and more particularly to the game of base ball, the 10 invention having for its primary object to provide a game board having a playing field marked or delineated thereon together with other appropriate indicia whereby an accurate account or score may be kept, and integral parts of said game board being separable or detachable therefrom for use as playing pieces.

More particularly, I provide the game board with a plurality of polygonal shaped 20 sections having indicia printed or marked thereon adjacent each edge thereof and connected at its several edges with the body of the game board by score lines incisions or by the provision of closely spaced sections 25 separated by perforations whereby such polygonal shaped parts may be readily pushed out or separated from the body of the game board. Each of these separated parts is adapted to be utilized as a spinning 30 top by inserting a suitable peg which may be conveniently whittled from wood, or other material or by inserting part of a toothpick through the center of the cardboard disc.

It is another important object of my invention to provide a game board for playing the game of base ball which is simple 35 and inexpensive and may, therefore, be distributed gratis as an advertisement, the necessity and expense of providing separate 40 accessories such as playing pieces or counters being eliminated.

With the above and other objects in view, the invention consists in an improved game, and in the several novel features thereof as 45 will be hereinafter more fully described, illustrated in the accompanying drawing, and subsequently incorporated in the subjoined claims.

In the drawing, wherein I have shown one 50 simple and satisfactory embodiment of the invention, and in which similar reference characters designate corresponding parts throughout the several views,—

Fig. 1 is a plain view of the game board; 55 Fig. 2 is a perspective view of one of the

playing pieces or tops separated from the board and indicating the same in a position relative to the base when spinning, and

Fig. 3 is a similar view showing the top in a position of rest.

In the embodiment of the device shown in the accompanying drawings, the game board 5 may consist simply of a rectangular sheet of heavy cardboard of suitable size having a smooth finished surface upon which the 65 playing field indicated at 6 in the form of the conventional base ball diamond is printed. Above this playing field the innings numbered 1 to 9 as shown at 7 are printed and enclosed within a suitable 70 printed box with a row of rectangular spaces 8 above and below the row of numerals. At the left hand side of these spaces 8, distinctive colors such as red and blue are printed.

At the right and left and sides of the 75 playing field or diamond 6, two parallel rows of rectangular boxes 9 are printed, the boxes in the outer row being numbered consecutively, 1, 2, 3, 4, 5, 6, 7, 8, 9, 0, and the boxes in the inner row being correspondingly 80 numbered but from 1 to 9 respectively. In these two rows of boxes, the respective players mark their scores in a manner to be hereinafter referred to.

Below the base ball field or diamond 6 85 provision is made for indicating the number of "outs" at 10 and the number of "strikes" at 11. All of the printed matter above referred to is preferably enclosed within a 90 printed rectangular border 12.

Outside of the border 12 and in one 95 marginal portion of the cardboard base a plurality of polygonal shaped sections 13 are preferably distinctively colored in colors corresponding with those representing the respective players. Preferably, these parts 13 are of octagonal shape and at each edge thereof the cardboard sheet is scored, incised, or provided with spaced perforations as indicated at 14, thereby weakening the connection between the parts 13 and the body of the cardboard. Adjacent the respective edges of each of the parts 13 the indicia

"1," "3," "Out at 1st," "2," "O," "S," "HR" 100 and "Fly" are respectively printed. At the center of each of these parts a perforation 15 is formed therethrough. Suitable instructions shown at 16 are printed upon the surface of the board relative to the use of the parts 13 and at the bottom of the board 105 110

below the rectangular border 9 the directions 17 for the proper playing of the game are printed thereon.

As shown in Figs. 2 and 3 of the drawings, in order to play the game, the players are provided with tops or playing pieces by pushing out two of the distinctively colored parts 13 and separating the same from the body of the cardboard and then whittling 10 a peg such as indicated at 18 or its equivalent and inserting the pointed end thereof through the perforation or opening 15 in the octagonal disc. Each of the players then spins his top and after it comes to a 15 position of rest on the table as shown in Fig. 3, the number adjacent the edge of the top resting on the table surface is noted and the player having the highest number has the choice of colors and is first at bat. 20 The player then again spins the top and if it stops with "O," "Fly" or "Out at 1st" at the lower side thereof, then the batter is cut and a pin or toothpick is impaled in the board adjacent the numeral 1 of the 25 "Outs" indicated at 10. If the numeral 1 is at the lower side of the top, a one base hit is indicated and a pin is impaled in the board at the first base of the diamond 6. If the "S" is at the lower side of the 30 top, the pin is impaled adjacent the numeral 1 of the "Strikes" indicated at 11. If the top rests at "O" or "Out at 1st," the pin is transferred to the numeral 2 of the "Outs" 10. Of course, three strikes also is one out 35 and three "outs" complete the inning for the player. If the "HR" on the top is at the lower side thereof this indicates a home run and all of the men on the bases represented by the pins score in advance of 40 the batter. The proper changes are made after each spinning of the top. The score is kept by impaling the pins in the two rows of boxes 9, the outer row indicating tens and the inner row units. During the 45 playing of an inning by each player, a pin is impaled in the board in the proper box 8 representing the inning being played. After nine innings have been played by the two players, the number of pins in 50 the rows of boxes 9 assigned to each player are counted and the one having the highest score wins the game. In the event of a tie, additional innings are played until one 55 player scores a run and is thus declared the winner.

From the foregoing description considered in connection with the accompanying drawings, it will be seen that I have devised a game for the playing of base ball which 60 may be very cheaply manufactured, in view of the fact that it is not necessary to provide dice, separate tops, special pins, counters or other accessories independent of the game board, as the playing pieces or 65 tops 13 constitute integral parts of the board

itself but are readily separable or detachable therefrom. While in the drawings I have shown the game board as provided with four such detachable playing pieces, it will be understood that a greater or lesser 70 number may be provided therein if desired. Upon the blank portions of the board surface within the border 12, any desired advertisements may be printed, and the game distributed gratis by manufacturers or advertisers. It will, of course, be understood that the game board can be made in any desired size and that it is not essential that the arrangement of the various indicia as shown in the drawing shall be strictly adhered to. The device is also susceptible of other modifications in the several detail features, and I accordingly reserve the privilege of resorting to all such legitimate changes as may be fairly embodied within 80 the spirit and scope of the invention as claimed.

I claim:

1. A game board of comparatively heavy material having parts spaced from a marginal edge of the board and each bounded by relatively weak portions of the board structure integrally connecting the part with the contiguous structure of the game board and normally retaining said part in fixed 90 relation to the game board, but readily yielding to pressure applied against one side of said part whereby said part may be projected from the plane of the board and separated therefrom for use as a playing piece.

2. A game board having a separable part integrally connected therewith and provided with centrally located means whereby said part may be fixedly connected with an operating member and spun in the manner of a top.

3. A game board having a playing field delineated thereon, and a plurality of parts having indicia printed thereon and adapted to be separated from the body of the game board, each of said parts having a central opening therein to receive a peg whereby said part may be utilized as a top.

4. A game board having a playing field delineated upon the surface thereof and bearing printed directions on said surface for playing the game, said game board also having a plurality of distinctively colored sections of polygonal shape having indicia printed thereon adjacent each edge thereof and adapted to be separated from the body of the board to provide playing pieces, and each of said playing pieces adapted to have a peg centrally inserted therethrough whereby the playing piece may be spun in the manner of a top.

5. An indoor base ball game comprising a cardboard base having a playing field and suitable indicia printed upon one surface

thereof together with directions for playing the game, said game board being further provided on said surface with a plurality of 5 distinctively colored sections of polygonal form, said sections adapted to be separated from the body of the game board and each having indicia printed thereon adjacent its respective edges and adapted to be centrally

engaged upon a suitable peg whereby said polygonal shaped piece may be spun in the 10 manner of a top.

In testimony that I claim the foregoing as my invention, I have signed my name. hereto.

EMIL BOMMER.
